DESIGN FOR A MOISTENER

Ottmar Kaub, St. Louis, Mo.

Application May 18, 1944, Serial No. 113,638

Term of patent 14 years

(Cl. D74—10)

To all whom it may concern:

Be it known that I, Ottmar Kaub, a citizen of the United States, residing in the city of St. Louis and State of Missouri, have invented a new, original, and ornamental Design for a Moistener, of which the following is a specification, reference being had to the accompanying drawing, forming part thereof.

Figure 1 is a side elevational view of a moistener showing my design.

Figure 2 is a plan view of the moistener shown in Figure 1, and

Figure 3 is a bottom view of the moistener shown in Figs. 1 and 2.

I claim:

The ornamental design for a moistener, substantially as shown.

OTTMAR KAUB.
